Primary Examiner — Jack Reickel(74) *Attorney, Agent, or Firm* — Danielson Legal LLC(57) **CLAIM**

The ornamental design for a display screen with a graphical user interface element, as shown and described.

DESCRIPTION

FIG. 1 is a first image in a sequence for a display screen with a graphical user interface element;

FIG. 2 is second image thereof;

FIG. 3 is a third image thereof;

FIG. 4 is a fourth image thereof;

FIG. 5 is fifth image thereof;

FIG. 6 is a sixth image thereof; and,

FIG. 7 is a seventh image thereof.

The appearance of the animated image on the display screen sequentially transitions between the images shown in FIGS. 1-7. The process in which, and the period during which, one image transitions to another image forms no part of the claimed design. The outermost broken line in the Figures illustrates a display screen and the remainder of the broken lines illustrate unclaimed portions of the animated graphical user interface. None of the broken lines form part of the claimed design.
